SWITCH

Application filed November 8, 1929, Serial No. 405,687, and in Germany November 7, 1928.

My invention relates to switching devices and particularly to high voltage disconnecting switches. It is an object of my invention to provide an improved combination of the 5 switching members and insulators with electrical devices such as for instance measuring transformers, grounding inductances and the like.

According to my invention the switching 10 devices are provided with hollow insulators and the electrical devices are arranged in the interior of the insulators of the disconnecting switch. In consequence thereof the construction of the switching plant is simplified 15 and a saving of material is obtained, since the insulators of the switch are arranged to form the insulating casings for the measuring transformers and the like. Furthermore any fault in the measuring transformers will be 20 remarked by the attendant much sooner than it would when the transformers were arranged in the commonly used manner at an inaccessible place of the plant.

It is a further object of my invention to 25 provide a multiple-piece insulator, and a set of measuring transformers, grounding inductances or the like, the single transformers being arranged in the single pieces of which the insulator is composed. When a current 30 transformer is arranged in the insulator, the terminals of the primary winding of the transformer may be arranged in such manner that the primary winding is inserted in the line when the disconnecting switch is 35 switched in. If voltage transformers or grounding inductances are arranged in high tension insulators, the terminals are connected in such manner that they connect the switching contact carried by the insulator to 40 ground.

It is still another object of my invention to provide a high tension disconnecting switch of the rotary type with three insulators, the middle one being rotatable and 45 carrying the movable contact member. In such rotary disconnecting switches the current transformer is preferably arranged in the middle insulator so that the current transformer is wholly switched off when the dis- 50 connecting switch is in its open position.

It is still another advantage of my invention that the insulating casings are heated by the heat produced in the windings and the iron of the devices arranged within the insulators. In consequence thereof the switches 55 will not be covered with ice as they would in outdoor stations at low temperatures.

In the accompanying drawing a preferred embodiment of my invention is illustrated diagrammatically by way of example in 60 vertical section.

Referring to the drawing, 13, 14, 15 are three high voltage insulators, the middle of one of which is rotatably supported on a ball bearing 12. 13' and 14' are contact members 65 carried by the insulators 13 and 14, respectively, contact member 13' being connected to the supply line, contact member 14' to the load circuit. 11 is the movable switch arm carried by the insulator 15 and terminating 70 in the movable contact members 16 and 18. The arm 11 may consist of insulating material or of conductive material. In the latter case the top piece 15' of the insulator 15 is made of insulating material. The conical shaft portions of the insulators 13, 14, 15 comprise several hollow parts 13a, 13b etc., 75 14a, 14b etc., and 15a, 15b etc., respectively, the joints of which are shielded by means of metal rings 22 arranged on the outer side 80 of the insulators. 19, 20 and 21 are current transformers arranged within the middle insulator 15. The primary winding of the transformer 19 is connected to the movable switch contact members 16 and 18 by means 85 of wires 16' and 18' traversing the arm 11. 17 is a resistor of high resistance connected in shunt to the primary winding of the transformer 19 and preventing the transmitting of overvoltages to the current transformer 19. 90 The primary winding of the current transformer 20 is connected to the secondary winding of the current transformer 19, and the primary winding of the current transformer 21 is connected to the secondary winding of the current transformer 20, while the secondary winding of the current transformer 21 is connected to an ammeter 34 by means of flexible connections 23. A voltage trans- 95 former consisting of single transformers 24 100

to 27 is arranged in the left-hand insulator 13, the secondary winding of transformer 27 being connected to a voltmeter 37. The primary winding of transformer 24 is connected 5 at one end to the contact member 13' and at the other end to the transformer core and the secondary winding of transformer 24. A grounding inductance is arranged in the right-hand insulator 14, it comprises four 10 parts 28 to 31 connected in series. The inductance 28 is connected to the contact member 14', the inductance 31 is connected to ground, so that a connection from the contact member 14' to ground through the grounding 15 inductance is established.

Plates 35 and 36 are provided in the insulators 13 and 14, respectively, carrying the voltage transformers 24 to 27 and the inductances 28 to 31, respectively. The plates 20 35 are provided with wall tube insulators 35' for the connections between the single voltage transformers arranged in the insulator 13. In the insulator 14 the plates 36 are electrically connected to the windings 25 of the inductances 28 etc. In the intermediate insulator 15 brackets 32 are provided carrying the current transformers 19 to 21. 33 is an actuating lever adapted to rotate the intermediate insulator 15.

30 The operation of this switching device is as follows:

When the device is in its closed position as shown in the drawing, the current flows from the supply circuit through stationary 35 contact member 13', movable contact member 16, conductor 16', primary winding of current transformer 19, conductor 18', movable contact member 18 and stationary contact member 14' to the load circuit. The 40 voltage is measured by means of the voltage transformer and the voltmeter 37. The current is measured by means of the current transformers 19 to 21 and ammeter 34. When the middle insulator 15 is rotated by means 45 of the actuating lever 33 and the disconnecting switch is moved into its open position, the current transformers 19 to 21 are wholly switched off and may be revised or replaced, while the supply voltage is still measured 50 by the voltage transformers 24 to 27 and the voltmeter 37.

55 My invention is not limited to insulators of the bracket type as shown in the drawing, it may also be used in wall tube or suspended insulators.

I wish it to be understood that I do not desire to be limited to the exact details of construction shown and described for obvious modifications will occur to a person 60 skilled in the art.

I claim:

1. In a high voltage disconnecting switch, a hollow supporting insulator, an electrical device comprising an iron core and a winding 65 cooperating with said core mounted within

said insulator, a switch element mounted at one end of said insulator and a high voltage connection leading from said switch element to said electrical device.

2. The device of claim 1 in which the said 70 electrical device is a current transformer.

3. The device of claim 1 in which the said electrical device is a voltage transformer.

4. The device of claim 1 in which the said 75 electrical device is a grounding inductance.

5. In a high voltage disconnecting switch, a hollow supporting insulator, a voltage reducing mechanism mounted within said insulator, a switch element mounted at one end of said insulator, a high voltage connection 80 passing through said end of said insulator and leading from said switch element to said voltage reducing mechanism, and a low voltage connection passing through the other end of said insulator.

85 6. The device of claim 5 in which the voltage reducing mechanism is an instrument transformer.

7. In a high voltage disconnecting switch, a hollow supporting insulator, a switch element constituting the line side of said disconnecting switch mounted on one end of 90 said insulator, a voltage transformer mounted within said insulator and a high voltage connection leading from said switch element 95 to the primary of said voltage transformer.

8. In a high voltage disconnecting switch, a rotatable hollow insulator, switch blades mounted on one end of said rotatable insulator, an instrument transformer mounted 100 within said insulator and high voltage connections leading from the said switch blades to the primary of said instrument transformer.

105 In testimony whereof I affix my signature.
FRANZ JOSEPH FISCHER.
